UNITED STATES PATENT OFFICE.

JOHN R. MEADOWCROFT, OF MONTREAL, QUEBEC, CANADA.

DRY-PIPE VALVE.

Application filed February 5, 1919. Serial No. 275,226.

To all whom it may concern:

Be it known that I, JOHN ROBERT MEADOWCROFT, a subject of the King of Great Britain, and resident of the city of Montreal, in the

5 Province of Quebec, Dominion of Canada, have invented certain new and useful Improvements in Dry-Pipe Valves; and I do hereby declare that the following is a full, clear, and exact description of the same.

10 My invention relates particularly to dry pipe valves of the differential type, this type being distinguished by the employment of compressed air at relatively low pressure to retain the valve closed against a relatively 15 high water pressure, this being accomplished by the presenting of a proportionately greater valve area to the air than to the water pressure, the function being to release the flow of water upon the air pressure being reduced by the opening of a sprinkler head for instance, thus causing that sprinkler head and any others in the same system which may be opened to spray the water in which the head or heads may be located.

20 The object of my invention is to render the opening operation of these valves more positive. A further object is to render the clapper more steady in its rocker arm and thereby cause it to effect a more perfect 25 closure.

Heretofore in valves of this type an extensive opening movement of the main valve was required to completely close the drip outlet valve with the result that a considerable 30 quantity of water was allowed to run to waste thereby lowering the pressure.

It is one of the objects of my invention therefore, to provide a construction in which the drip outlet valve is closed with a minimum 35 opening movement of the main valve.

To this end the invention may be said broadly to consist of the combination with a differential dry pipe valve of the type described, of a pivoted rocker arm; a counter-weight and means whereby the counter-weight exerts a leverage upon the rocker arm. The invention also consists of a pivotal connection between the clapper proper and its rocker arm which, in combination 45 with a concentric curved rib on the under side of said rocker arm, insures that the valve proper is steadied and prevented from undue rocking thus augmenting its perfect seating. Another feature of the invention 50 consists of a pivoted gravity tension pawl for the purpose of preventing the valve

from returning to its seat once it has left the same.

The invention also consists of the construction, combination and particular arrangement of parts hereinafter described and pointed out in the claims.

For full comprehension, however, of my invention, reference must be had to the accompanying drawings in which similar reference characters indicate the same parts, and wherein:

Figure 1 is a longitudinal sectional view through the centre of my improved valve, taken on line 1—1 Figure 5; 70

Figure 2 is an enlarged detail elevation partly in section of the valve for controlling the drip outlet;

Figure 3 is a plan view thereof;

Figure 4 is a plan view of the gravity tension pawl;

Figure 5 is a horizontal sectional view taken on line 5—5 Figure 1; and

Figure 6 is a vertical sectional view taken on line 6—6 Figure 1. 80

The body of my improved valve, excepting for its particular design to accomodate my improved valvular mechanism, is practically the same as those heretofore known in that it has water inlet 2 and discharge 3, 85 valve connection 4 for testing for water in the air system, air supply line connection 5, water valve seat 6, air valve seat 7, connection 8 to automatic alarm system, connection 9 for drip, and draw off outlet 10. In addition to these features there is a rest or stop 20 to limit the opening movement of the valve, as will be presently shown.

The main valve clapper is indicated at 25 and is provided with a concentric circular 95 shoulder 26 corresponding in size and coinciding with the water seat 6, and clamped in its rim is a flat flexible valvular ring 27 preferably consisting of rubber. The relative diameter of the valve clapper and the seat 7 are such that the valve clapper fits within the seat and the valvular ring bears upon the seat, the clamping ring 28 being extended radially to overhang the under edge of the valve clapper and press the flexible ring upon its 105 seat. This valve clapper 25, is pivoted in a rocker arm 30 which also carries a counter-weight 35, which is in pivotal relation with the rocker arm and free to move in one direction relatively thereto, and when in normal 110 position is seated in a rest frame 40 which is an integral part of the rocker arm and exerts

a leverage on the latter and tends to hold the valve clapper upon its seat.

This rocker arm consists of an arm 30 with a relatively heavy hub 31 by which is pivoted 5 on an axle 32 carried by the casing.

The movement of this arm is limited by a lug 33 carrying a cushion 34 adapted to be engaged by the stop 20 when the valve clapper has moved to full open position.

- 10 The counterweight is made in the form of two half spheres and is mounted on an axle 36 in the upper end of a link 37, the other end of which works about an axle 38 between a pair of lugs 39 integrally formed 15 with the hub 31 of the carrier. This link 37 is connected to the axle 36 between the members of the counterweight. The eye in the link through which the axle 36 is inserted is preferably of sufficiently greater 20 diameter than the axle to permit the required play of the counterweight when the valve mechanism is in operation or being reset after operation.

The rest is in the form of a frame 40, the 25 sides of which are spaced a sufficient distance apart to accommodate the link, while a ratchet arm 41 presents with the frame a semi-annular form with tangential end, the arm having teeth 410 in its outer edge, the 30 counterweight being seated in this frame.

The gravity tension pawl is preferably a casting 50 cored out to receive a lead loading 35 filler 51 by which its head is weighted, its tail is forked, the prongs 52 of which are spread apart, as shown in Figure 4 for the purpose of preventing any side rocking of the pawl on its axle and ensuring its perfect central alignment and proper engagement of its lip 56 with the ratchet teeth. The 40 prongs 52 are journalled upon an axle 54 through eyes 55 of sufficiently larger diameter to permit a certain amount of play, while the head of the pawl has a lip 56, and the pivot point 54 is disposed in the centre 45 line of the body of the pawl. This pawl and more particularly its lip and the teeth of the ratchet arm are so relatively arranged that the pawl rests upon the end tooth of the ratchet arm without engaging 50 it when the valve is in closed position and engages one or the other of the teeth and prevents the valve clapper from closing back upon its seat, in the event of it being partially opened and then the opening force 55 momentarily released.

The pivotal connection between the valve and rocker-arm consists of a stud 12 having a shoulder 13 and screw-threaded shank 14 upon which the nut 15 is screwed, the shoulder serving as a distance piece to enable the nut to be screwed home against it without bearing upon the arm 30 and thus allowing a certain amount of oscillation between the valve plate and the rocker arm. 60 The arm is of sufficient length to reach be-

yond the stud almost to the opposite periphery and the under side of the arm has a curved rib or boss 17. This curved rib or boss is concentric with the stud 12, and has the same radius as the free end of the arm 70 which is correspondingly curved; while a central boss 18 on the valve clapper is of a sufficient thickness to space the end of the arm and the boss 17 slightly from the valve clapper. This formation tends to steady the 75 valve clapper in its rocker arm and to ensure a perfect seating simultaneously of the valve clapper over its whole seating area.

When the air holding the valve closed is reduced in pressure down to a predetermined point, the valve will open. As it opens the rest frame carries the counterweight over until its center of gravity passes the point at which it is pivoted to the rocker arm, after which it falls over, the link bearing upon the lug 33 and the leverage thus brought into action is thereby transmitted to the rocker arm which supplements the inflowing water pressure in throwing the valve to full open position. As the counterweight rests in full normal position, in rest 90 40 and bears towards the valve clapper it tends to retain the latter closed.

In order to return the counterweight to its normal position in its rest frame after 95 the valve has operated, a pull rod 70 is pivoted at one end to the axle 36 and passes through a guide preferably in the form of a vertically elongated hole 71 in a lug 72 cast on the rest frame. This rod projects towards the hand hole 75 and is of sufficient length to accommodate the operation of the counterweight. The outer end of the rod has a T-handle 76.

The gravity check valve controlling the 105 drip outlet 9 comprises a pair of levers 80 and 81. The lever 80 carries the valve proper and is of substantially bell-crank form the free end of one arm of which is comparatively short having a ball 82 formed 110 integrally thereon, this ball overhanging the valve seat and being adapted to rest thereon and close the drip outlet when the main valve is opened beyond a predetermined extent. The valve seat is constituted by a 115 bushing 83 screwed into the valve casing and having an upwardly tapered bore 84 and a pair of lugs 88 between which the lever 80 is fulcrumed. The other arm 85 of the bell-crank lever projects upwardly a distance 120 sufficient to overlap the lower end of the lever 81 which is counterweighted as at 86. The latter lever is fulcrumed in a bracket 87 secured to the valve casing and its upper 125 end projects across the path of the main valve clapper for the purpose of causing the lower end to engage the arm 85 and lift the valve off its seat when the main valve clapper is moved to closed position. It will be noted that the points of fulcrum of the 130

levers are so positioned that a minimum opening movement of the main valve produces a much greater extent of movement of the ball 82 and which latter movement is 5 substantially in the axial line of the valve seat thereby ensuring a uniform setting of the ball upon its seat and obtaining a quick-closing action thus obviating any unnecessary waste of water and the consequent reduction in pressure.

When the main valve clapper is open and the ball 82 is closing the drip outlet the lower end of the lever 81 is adapted to rest upon the ball thereby adding to the weight 15 of the latter the weight of the counterweight of the lever.

Operation.

In the event of the air pressure in the 20 valve chamber being reduced below a predetermined point by the opening of a sprinkler head in the pipe line (not shown) communicating with the discharge opening 3, the pressure of the water upon the main 25 valve clapper 25 throws the latter off its seat and the clapper under the influence of the counter-weight 35 is caused to assume and maintain the position indicated in dotted lines in Figure 1, and communication 30 is established between the inlet opening 2 and the outlet 3.

In the event of a slight lowering of the air pressure in the valve chamber and the main valve clapper 25 opens to an extent 35 not sufficient to overthrow the counter-weight the water admitted to the valve chamber will be discharged through the drip outlet 9 when the main valve clapper again becomes seated.

40 What I claim is as follows:

1. In a dry pipe valve, the combination with a pivoted arm for carrying the valve and the valve carried thereby, of a counter-weight movable relatively to the carrying 45 arm, and means pivotally connecting the counterweight to the said carrying means whereby the opening of the valve is accelerated.

2. In a dry pipe valve of the type 50 described, the combination with a pivoted arm for carrying the main valve having a substantially semi-circular rest frame disposed with its center above the pivot and slightly towards the free end of the arm; a counter-weight adapted to be received in the rest 55 frame; a link having the counterweight pivotally carried at one end and the opposite end being pivoted to the arm at a point between the pivot of the arm and the center of the rest frame and off-centered relatively thereto; and means upon the arm for limiting the movement of the link and counterweight relatively to the rest frame.

3. In a dry pipe valve of the type 60 described, the combination with a pivoted arm

for carrying the main valve having a substantially semi-circular rest frame disposed with its center above the pivot and slightly towards the free end of the arm; a counter-weight adapted to be received in the rest 70 frame; a link having the counterweight pivotally carried at one end and the opposite end being pivoted to the arm at a point between the pivot of the arm and the center of the rest frame off-centered relatively 75 thereto; means upon the arm for limiting the movement of the link and the counter-weight relatively to the rest frame, and means for returning the counterweight to normal position.

4. In a dry pipe valve of the type described, a pivoted rocker arm for carrying the main valve clapper having a substantially semi-circular rest frame disposed with its center above the pivot and slightly towards the free end of the arm; a counter-weight adapted to be received in the rest frame; a link having the counterweight pivotally carried at one end and the opposite end being pivoted to the rocker arm at 90 a point between the pivot of the rocker arm and the centre of the rest frame and off-centered relatively thereto; and a rigid lug upon the rocker arm for limiting the movement of the link and counterweight 95 relatively to the rest frame.

5. In a dry pipe valve of the type described, a pivoted rocker arm for carrying the main valve clapper having a substantially semi-circular rest frame disposed with its centre above the pivot and slightly towards the free end of the arm; a counter-weight adapted to be received in the rest frame; a link having the counterweight carried at one end and the opposite end being pivoted to the rocker arm at a point between the pivot of the rocker arm and the centre of the rest frame and off-centered relatively thereto; and means upon the rocker arm for limiting the movement of the link and counter-weight relatively to the rest frame, and means for limiting movement of the rocker arm.

6. In a dry pipe valve of the type described comprising a valve case having an 115 inlet with valve seat and an outlet, of an arm, a clapper carried by the arm in position to register with the valve seat, one end of the arm being offset in the form of a hub; means pivoting the offset end of the 120 arm at a point at one side of the valve seat; a link pivoted at one end to the arm; a counterweight carried by the opposite end of the link and means whereby the inertia of the counterweight is utilized to accelerate the opening of this valve.

7. In a dry pipe valve of the type described comprising a valve case having an 125 inlet with valve seat and an outlet, of an arm, a clapper carried by the arm in posi-

- tion to register with the valve seat, one end of the arm being offset in the form of a hub; means pivoting the offset end of the arm at a point at one side of the valve seat; a link pivoted at one end to the arm; a counterweight carried by the opposite end of the link; and means carried by the arm and adapted to be engaged by the link when the clapper is moved to open position.
10. In a dry pipe valve of the type described comprising a valve case having an inlet with a valve seat and an outlet, of an arm, a clapper carried by the arm in position to register with the valve seat, one end of the arm being off-set in the form of a hub; the valve casing having an integral stop at one side of the seat; means pivoting the arm at a point between said stop and valve-seat; a link pivoted at one end to the arm; a counterweight carried by the opposite end of the link; means carried by the arm and adapted to be engaged by the counterweight when the valve is moved to closed position; and means whereby the inertia of the counterweight is utilized to accelerate the opening of the valve, said last mentioned means being adapted to engage and be stalled by the stop.
9. In a dry pipe valve of the type described comprising a valve case having an inlet with a valve seat and an outlet, of an arm, a clapper carried by the arm in position to register with the valve seat, one end of the arm being off-set in the form of a hub; the valve casing having an integral stop at one side of the seat; means pivoting the arm at a point between the said stop and valve-seat; and the said arm having a lug adapted to engage and be stopped by the said stop; a link pivoted at one end to the arm; a counterweight carried by the opposite end of the link; and means carried by the arm and adapted to be engaged by the counterweight when the valve is moved to closed position.
10. In a dry pipe valve of the type described comprising a valve case having an inlet with a valve seat, and an outlet, of an arm, clapper carried by the arm in position to register with the valve seat, one end of the arm being offset in the form of a hub; means pivoting the offset end of the arm at a point to one side of the valve seat; the valve casing having an integral stop contiguous to the pivot of the arm; a link pivoted at one end to the arm; a counterweight carried by the opposite end of the link; a rest-frame carried by the arm; and a lug carried by the arm and adapted to be engaged by the link when the clapper is moved to open position whereby the inertia of the counterweight is utilized to accelerate the opening of the valve.
11. In a dry pipe valve of the type described comprising a valve case having an
- inlet with a valve seat and an outlet, of an arm, a clapper carried by the arm in position to register with the valve seat, one end of the arm being offset in the form of a hub; means pivoting the offset end of the arm at a point to one side of the said valve seat; the valve casing having an integral stop contiguous to the pivot of the arm; a link pivoted at one end to the arm; a counterweight carried by the opposite end of the link; means carried by the arm and adapted to be engaged by the counterweight when the valve is moved to closed position to employ the pressure in the closing of the valve, the said rest frame consisting of a substantially semi-circular member; means carried by the arm and adapted to be moved by the counterweight when the clapper is moved to open position whereby the inertia of the counterweight is utilized to accelerate the opening of the valve, and means for coacting with the rest frame for retaining the same and holding the valve in open position.
12. In a dry pipe valve of the type described comprising a valve case having an inlet with a valve seat and an outlet, of an arm, a clapper carried by the arm in position to register with the valve seat one end of the arm being offset in the form of a hub; means pivoting the offset end of the arm at a point to one side of the said valve seat; the valve casing having an integral stop contiguous to the pivot of the arm; a link pivoted at one end to the arm near the base of the lug; a counterweight carried by the opposite end of the link, a rest frame carried by the arm and adapted to be engaged by the counterweight when the valve parts are set in their normal closed position and for the purpose of employing the weight in keeping the clapper closed, the rest frame consisting of a semi-circular member having a plurality of teeth on its periphery; a gravity pawl for engaging the teeth and retaining the valve in open position, means carried by the arm and adapted to be engaged by the counterweight when the clapper is moved to open position whereby the inertia of the counterweight is utilized to accelerate the opening of the valve.
13. In a dry pipe valve of the type described comprising a valve case having an inlet with a valve seat and an outlet, of an arm, a clapper carried by the arm in position to register with the valve seat, one end of the arm being offset in the form of a hub; means pivoting the offset end of the arm at a point to one side of the said valve seat; the valve casing having an integral stop contiguous to the pivot of the arm; a link pivoted at one end to the arm; a counterweight carried by the opposite end of the link; means carried by the arm and adapted to be engaged by the counterweight when the valve is moved to closed position to employ the pressure in the closing of the valve, the said rest frame consisting of a substantially semi-circular member; means carried by the arm and adapted to be moved by the counterweight when the clapper is moved to open position whereby the inertia of the counterweight is utilized to accelerate the opening of the valve.

clapper is moved to open position whereby the inertia of the counterweight is utilized to accelerate the opening of the valve; a rest frame carried by the arm and adapted 5 to be engaged by the counterweight when the valve parts are set in their normal closed position and for the purpose of employing the weight in keeping the clapper closed the said rest frame consisting of a semi-circular 10 member having a plurality of teeth on its periphery; a gravity tension pawl with its engaging tooth upon its underside, such pawl being pivoted in the case with its pivot point in substantially the center line of the 15 mass of the pawl.

14. In a dry pipe valve, the combination with a pivoted valve carrier, and the valve carried thereby, of a counterweight mounted upon and movable relatively to the carrier, 20 means on the valve carrier for carrying the counterweight, and a manually operated device upon the counterweight-carrying means constructed and arranged to exert a pull upon the counterweight for the purpose of 25 returning the counterweight to normal position.

15. In a dry pipe valve of the type described, the combination with a valve casing, a valve clapper, a rocker arm pivoted at one 30 end in the casing adjacent the periphery of the clapper and constructed and arranged to carry the same substantially midway its length, said arm being comparatively wide and extending from its point of fulcrum 35 parallel to and diametrically across the top of the clapper, means effecting a loose connection between the arm and clapper, and means for limiting relative movement therebetween, said last mentioned means consisting 40 of a transverse rib upon the underside of the arm adjacent its point of fulcrum and a downward projection upon the free end of the arm.

16. In a dry pipe valve of the type de-

scribed, the combination with a valve casing, a valve clapper and valve seat, a carrier for the valve clapper, a curved member rigidly mounted upon said carrier and movable relatively thereto and extending upwardly substantially at right angle to the 45 carrier, said member having a plurality of teeth; of a comparatively short gravity tension pawl having a substantially straight body and an engaging lip upon its underside, such pawl being counterweighted at its 50 free end and pivoted in the casing with its pivot point in substantially the center line of the body of the pawl, said pawl being constructed and arranged to engage the said 55 teeth of the member for the purpose of preventing the valve clapper from returning to its seat when raised.

17. In a dry pipe valve of the type described, the combination with the valve casing having an inlet and outlet and a drip 60 outlet and a main valve clapper movable to and from the said inlet for the purpose of controlling the same; of a gravity check valve controlling the said drip outlet, said 65 check valve consisting of a valve seat, a gravity valvular member fulcrumed in close proximity to the valve seat, and a lever fulcrumed in close proximity to its upper end and counterweighted at its lower end the 70 upper end of said lever being normally in bearing relation with the underside of the main valve clapper and the lower end being in operative relation with the said valvular member and adapted to maintain the latter 75 in open position when the main valve is in 80 closed position.

In testimony whereof I have signed my name to this specification in the presence of two witnesses.

JOHN R. MEADOWCROFT.
